UNITED STATES PATENT OFFICE.

MARCUS D. MOORE, OF WAVELAND, INDIANA, ASSIGNOR TO FRANKFORT NOVELTY COMPANY, OF FRANKFORT, CLINTON COUNTY, INDIANA.

CAN OPENER.

Application filed February 5, 1923. Serial No. 617,085.

To all whom it may concern:

Be it known that I, MARCUS D. MOORE, a citizen of the United States, residing at Waveland, in the county of Montgomery and
5 State of Indiana, have invented certain new and useful Improvements in Can Openers; and I do hereby declare the following to be a full, clear, and exact description of the invention, such as will enable others skilled in
10 the art to which it appertains to make and use the same.

This invention relates to improvements in that type of can openers designed to be swung pivotally about a can top or a portion thereof, and has as its object the easy and efficient removal of a can top in a manner leaving the body of the can entirely open and free of overhanging parts or jagged edges for allowing discharge of the contents of the can in its entirety.

With this and further objects in view as will in part hereinafter become apparent and in part be stated, the invention comprises certain novel constructions, combinations and arrangements of parts as subsequently specified and claimed.

In the accompanying drawings,—

Figure 1 is an inverted plan view of a can opener embodying the features of the present invention, the cutting blade being shown in full lines in an inoperative position and in dotted lines in an operative position.

Figure 2 is a plan view of the same with the cutting blade seen in an operative position.

Figure 3 is a transverse, vertical section taken on the plane indicated by line 3-3 of Figure 2 and looking in the direction indicated by the arrows, the parts being shown on a greatly enlarged scale.

Figure 4 is a fragmentary, edge view of the parts on the scale seen in Figure 3.

Referring to the drawings by numerals, 1 indicates an elongated, slotted plate which, because of its function, will be hereinafter referred to as the handle. One end portion of the handle or plate 1 terminates in an integral or appropriately affixed shank 2 having a penetrating point 3. The shank 2 is bent or curved laterally so that the penetrating point 3 faces in the same direction as one of the edges of the handle 1, whereby the operator in grasping handle 1 may exert downward pressure on the point 3 for forcing it through the metal of a can cap

without the assistance of a hammer or other instrument. The shank 2 is sufficiently narrow for leaving shoulders at the place of juncture with the handle 1, so that when the shank has entered the can cap to the requisite extent further introduction will be intercepted by contact of the shoulders with the surface of the top of the can. 60

The handle 1 is provided with a longitudinal central slot 4, and at one face of the handle is arranged a cutting blade 5 and at the other a detent plate 6. That face of the handle 1 at which appears the plate 6 may properly be referred to as the upper face since it is that face which is exposed upwardly when the instrument is in operative position in engagement with a can, and the relative location of the parts will be herein-after mentioned with this disposition of the instrument in mind. Also, the end of the handle 1 having the shank 2 will be referred to as the front end for convenience, and other parts correspondingly referred to.

The blade 5 consists of a flat plate resting for the major portion of its length against the under face of handle 1 and offset toward the front portion of the blade, as indicated at 7, so that the cutting edge 8 of the blade 5 is spaced from the under face of the handle 1, whereby the cutting edge 8 is adapted to engage a portion of the can body slightly below the top of the can when the shank 3 is in position penetrating the can top and the handle 1 rests horizontally on the can. The cutting edge 8 is preferably inclined or oblique to the edges of the plate forming the blade 5, so that the foremost terminus of the cutting edge 8 forms a penetrating point, as clearly seen in Figure 1. As the plate forming the blade 5 is made preferably

of light sheet material, and as it is desirable that such blade shall possess considerable stability, the plate is stiffened by having corrugations 9, 9 stamped longitudinally therein, the said corrugations extending 100 from points toward the rear portion of the blade longitudinally thereof up the offset portion 7 and terminating just short of the cutting edge 8. The blade 5 and plate 6 are connected preferably by a rivet consisting 105 of an enlarged central portion 10 and reduced terminal portions 11, 11, one of the terminal portions penetrating the blade 5 and the other the plate 6, and each being swaged up to form a rivet head for pivotally 110

connecting the plate and blade. The enlarged portion 10 is of a size sufficient to snugly fit within the slot 4 so as to hold the connected parts in proper alinement while 5 leaving them free to have the required slight pivotal action.

- The handle 1 is formed along one edge of slot 4 with a ratchet of appropriate serrations 12, and the plate 6 at its rear end 10 is provided with a rearwardly extending tongue bent downwardly to an offset position, indicated at 13, the offset portion 13 of the tongue being thus arranged in the slot 4 in position to be swung into and 15 out of any of the notches or serrations 12. The blade 5 at one edge is provided with an upwardly bent lip 14, which extends past the edge of the handle 1 and past the corresponding edge of the plate 6, the plate 20 being provided with an offset projection 15 extending in position for being engaged by the lip 14. At the opposite side of the plate 6 from lip 14, the plate 6 is provided with an upwardly extending lip 16, 25 the two lips 14 and 16 being so arranged that in operation the handle 1, being grasped in the hand of the operator, will naturally fall in such a position as to enable the thumb of the operator to rest 30 against the outer face of the lip 16 while the fore-finger of the operator engages the outer face of the lip 14 so that the parts may be readily stressed to the position retaining the tongue 13 in engagement with 35 any one of the notches 12. Release of such engagement may be effected merely by relieving the pressure of the fore-finger on the lip 14 and the exertion of pressure by the thumb on lip 16. Such a shifting of 40 pressure will cause the tongue 13 to move from the position seen in Figure 2 out into the central portion of the slot, as seen in full lines in Figure 1, whereupon the blade 5 and plate 6 are free to slide longitudinal- 45 ly of the handle 1 as may be required.
- In operation, the penetrating point 3 is forced through the top of the can as nearly as possible at the central point of the top, and the handle 1 is moved from its edge-wise position down to a flat position resting on top of the can, the shank 2 entering the aperture formed by the penetrating point during the movement of the handle to its lowered position. The blade 5 and 50 plate 6 will, in the meantime, have been shifted toward the rear of the handle, as indicated in dotted lines in Figure 1, so as to be clear of the can until the handle is in proper position. Then the blade and 55 plate are moved toward the can until the penetrating point of blade 5 enters the side wall of the can. The handle is then swung clockwise about the can, the cutting edge 60 65 8 severing the wall of the can itself up near the line of the cap, and as soon as

the handle has completed one rotation about the can, the entire top of the can will be severed and may be removed, leaving the upper end of the can completely free for enabling discharge of the contents in its 70 entirety, thus avoiding the bruising of fruit or other substances and detracting from the appetizing appearance thereof. It is to be noted that if the operator fails to get the point 3 exactly in the center of the 75 can top, any slight difference may be compensated for by the length of the inclined cutting edge 8, but in case the center is missed by a distance greater than the distance represented by such incline additional 80 compensation may be provided by shifting of the blade 5 inward or outward as required during the course of the cutting operation.

What is claimed is:—

1. In a can opener, the combination, with a handle, and a penetrating point therefor, of a cutter blade engaging the handle and adjustable longitudinally thereof, a detent plate connected to the blade and movable relative thereto to and from a position for retaining the blade at any of its adjusted positions, means carried by the blade for shifting the detent plate to the retaining position, and a projection extending from the detent plate into position for being engaged by said shifting means.

2. In a can opener, the combination, with a handle, and a penetrating point therefor, of a cutter blade engaging the handle and adjustable longitudinally thereof, a detent plate connected to the blade and movable relative thereto to and from a position for retaining the blade at any of its adjusted positions, means carried by the blade for shifting the detent plate to the retaining position, and means on the plate for shifting the same out of the retaining position.

3. In a can opener, the combination, with a handle having a penetrating point, and a longitudinal slot, of a blade at one side of the handle, and a detent plate at the other, means pivotally connecting the blade and plate through the slot, the handle being formed with locking notches along one edge of the slot, a projection extending from the detent plate into the slot in position for being shifted pivotally to and from engagement with any one of the notches, and a lip extending from the blade past the edge of the handle in position for engaging and stressing the detent plate toward a position of engagement of the projection with a notch.

4. In a can opener, the combination, with a handle having a penetrating point, and a longitudinal slot, of a blade at one side of the handle and a detent plate at the other, means pivotally connecting the blade and plate through the slot, the handle being

formed with locking notches along one edge of the slot, a projection extending from the 5
detent plate into the slot in position for being shifted pivotally to and from engagement with any one of the notches, a lip extending from the blade past the edge of the handle in position for engaging and stressing the detent plate toward a position of engagement of the projection with a notch, 10
and a lip extending from that edge of the detent plate opposite the place of engagement of the blade-carried lip.

5. In a can opener, the combination, with a handle having a penetrating point and a 15
longitudinal slot, of a cutting blade at one face of the handle and a detent plate at the other, a rivet pivotally connecting the plate and handle and dimensioned to transversely fill the slot, and means for locking the detent 20
plate at various points of adjustment along the handle.

6. In a can opener, the combination, with a handle formed of a flat plate slotted longitudinally and having a terminal penetrating 25
point, of a cutting blade at one face of the handle, a detent plate at the other face of the handle, a pivotal connection between the blade and plate extending through the slot, the handle being formed with a series of 30
notches opening into the slot, a projection on the detent plate adapted to move freely within the slot and to be moved pivotally into and out of the notches, a lip projecting from the blade past the detent plate in 35
position for engaging the edge of the detent plate and stressing the same toward a position of interlock of the projection with a notch, and a lip turned from the detent plate

to extend in the same direction as the first- 40
mentioned lip and spaced therefrom substantially for the width of the handle.

7. In a can opener, the combination, with a handle having means of pivotal engagement with a can, of a cutting blade engaging and shiftable longitudinally of the 45
handle, and a detent connected to the blade and shiftable edgewise independently of the blade into engagement with the handle for locking the blade in various operative positions along the handle.

8. In a can opener, the combination, with a handle having means of pivotal engagement with a can, of a cutting blade engaging and shiftable longitudinally of the 50
handle, the handle being formed with notches, and a plate pivoted to the blade to swing edgewise of the blade into and out of engagement with said notches.

9. In a can opener, the combination of a handle having means of pivotal engagement 60
with a can, said handle being of relatively thin flat material and formed with a longitudinal slot notched at one side, a cutting blade, and a plate pivotally connected by means extending through the slot, and the 65
plate being formed with a projection extending into the slot and adapted to enter any of said notches incident to pivotal movement of the plate.

In testimony whereof I affix my signature 70
in presence of two witnesses.

MARCUS D. MOORE.
